CORUNDUM PHONOGRAPH NEEDLE AND
SOUND REPRODUCING APPARATUS EM-
BODYING SAMEJohn F. Pelton, Kenmore, and Thomas F. Hart,
Buffalo, N. Y., assignors, by mesne assignments,
to Union Carbide and Carbon Corporation, a
corporation of New York

Application July 18, 1947, Serial No. 761,812

8 Claims. (Cl. 274—38)

1

This invention relates to extending the playing lives of unicyrstalline corundum phonograph needles, especially needles of the composite type wherein a small unicyrstalline corundum point is secured in the end of a shank of different material, such as metal or plastic.

Composite phonograph needles having unicyrstalline corundum points, such as natural or synthetic ruby and sapphire, have been used extensively in recent years. Because of their great hardness such needles theoretically should have extremely long playing lives. It has been found, however, that ruby and sapphire needle points are quite erratic in behavior, some having relatively long lives and others failing in service after only relatively short periods. When premature failure occurs it is usually by the spalling or chipping of particles from the needle points rather than by ordinary abrasion. This problem has been of considerable concern in the art of sound transcription, but attempts to solve it met with little success prior to the present invention.

The principal object of this invention is to extend and make more uniform the playing lives of phonograph needles having unicyrstalline corundum points.

In the drawing:

Fig. 1 is a schematic perspective view showing a corundum phonograph needle point in playing position on a phonograph record, the size of the needle point being considerably exaggerated;

Fig. 2 is an enlarged side elevational view, parts being in section, of a composite phonograph needle mounted in playing position in a phonograph tone arm; and

Fig. 3 is an enlarged front elevational view of the phonograph needle shown in Fig. 2.

We have found, surprisingly, that the life of a composite sound reproducing needle N having a unicyrstalline corundum point 11 can be lengthened considerably by properly positioning the needle on a laterally modulated record R so that two conditions are observed with reference to the crystallographic c-axis c—c of the needle point. Condition No. 1 is that needle point 11 should be maintained in such a position during the playing of a record R that its c-axis c—c is approximately parallel to the record. Condition No. 2 is that the cg plane, defined by the c-axis c—c and the longitudinal axis g—g of the needle point, should be approximately tangent to the spiral groove 13 of the record wherever the needle is in contact with the record (approximately normal to the record radius).

As a practical commercial matter, it is not

possible to fulfill both of the above conditions perfectly on all needles, but a variation of plus or minus 15 degrees in either or both conditions can be tolerated without sacrificing much in the uniformity and extent of life of the needles.

The necessity for observing both of the above-described conditions is emphasized by the following results of a series of accelerated life tests conducted on a large number of composite needles 10 with sapphire points mounted in metal shanks and carried in a tone arm which exerted a needle force of 1½ ounces on disc type record R.

A. Of the needles which were so mounted that both of the above described conditions No. 1 and 15 No. 2 were observed within plus or minus 15 degrees, 88% were still in satisfactory condition after 300 minutes of playing time.

B. Of the needles which were so mounted that the c-axis c—c was approximately parallel to the 20 record within plus or minus 15 degrees (condition No. 1), but that the cg plane was inclined at an angle of more than 15 degrees to the tangent to the record groove, only 50% were still in satisfactory condition after 300 minutes of playing 25 time.

C. Of the needles which were so mounted that the cg plane was approximately tangent to the record groove within plus or minus 15 degrees (condition No. 2), but that the c-axis c—c was 30 inclined at an angle of more than 15 degrees to the record, only 30% were still in satisfactory condition after 300 minutes of playing time.

D. Of the needles which were so mounted that neither of the above described conditions No. 1 35 and No. 2 was observed within plus or minus 15 degrees, only 10% were satisfactory after 300 minutes of playing time. Many of the unsatisfactory needles failed after much less than 300 minutes, in several instances lasting for less than 40 30 minutes.

In all of the above tests, the points of the unsatisfactory needles were too badly chipped or spalled to be used longer.

Deviations of the c-axis c—c and the cg plane 45 of more than 15 degrees from one or both of the two critical conditions No. 1 and No. 2 cause a sudden large decrease in the percentage of satisfactory needles. For example, of a group of needles wherein the deviation from the optimum 50 of one or both conditions was between 15 and 30 degrees (but neither condition greater than 30 degrees), only 67% were satisfactory in life tests comparable to those described above.

It is apparent that on an extra large disc type 55 record or on a record where the radius of the rec-

ord groove is infinitely large, for example a recording tape, tangency of the cg plane to the groove is then for practical purposes identical with parallelism to the groove and condition No. 2 is fulfilled by positioning the needle point so that the cg plane is parallel to the record groove.

The average user of phonograph needles has no facilities for determining the position of the c -axis in a corundum needle point. To make available to the public the advantages of our invention, therefore, it is essential for the manufacturer of phonograph needles to mount the corundum needle point 11 in a shank 15 in such a way that conditions No. 1 and No. 2 will necessarily be observed by the ultimate consumer when he mounts the needle in his tone arm or pick-up T. This is done by providing each needle N with a suitable index so disposed with reference to the cg plane of the point 11 and the c -axis direction of the point that when the needle is positioned in a phonograph tone arm with the index in a position determined by a prearranged code of instructions the cg plane is approximately tangent to the groove or sound track 13 of a record R to be played, and the c -axis $c-c$ of the point is approximately parallel to the record. Any suitable index may be used, for example an indentation, a surface mark, or a hole.

A convenient and practical index is the set screw seat of the needle which generally is a flattened side of the needle shank as shown at 17 in Fig. 2. In most modern phonographs the needle set screw 19 is located horizontally in the extreme end of the tone arm T, and the needle socket 21 is inclined at an angle of about 65° to the record R in the direction of record rotation. In most cases, therefore, the proper positioning of the needle is assured when the corundum point 11 is so set in the lower end of shank 15 that the cg plane of the point approximately bisects the set screw seat 17, as shown in Fig. 3, and the c -axis $c-c$ forms an angle of about 65° with the longitudinal axis L-L of the top portion of shank 15 on the side of the longitudinal axis remote from set screw seat 17.

Many different shapes of set screw seats can be used, such as flat, concave, grooved, or V-shaped. However, the usual set screw seat is flat as shown at 17, so that the proper setting of most needle points in their shanks requires that the cg plane be approximately normal to such a flat seat.

When an index as described above is provided, proper positioning of the needle point on the record is independent of the needle shape. Both straight needles and needles having simple and complex curvatures can be positioned properly.

In the case of the popular S-shaped needles, such as the needle N illustrated in Fig. 2, the plane of the S-curve is normally maintained approximately tangent to the record groove 13 when the needle is in playing position. In such a needle the advantages of the present invention are provided by so setting point 11 in shank 15 that the cg plane approximately parallels the plane of the S-curve and the c -axis $c-c$ lies at about 65° to the longitudinal axis L-L of the upper portion of shank 15 on the side of axis L-L remote from point 11. Proper positioning of the needle point is obviously independent of the location of the set screw seat on such a needle.

When the needle is of the so-called permanent type which a phonograph manufacturer mounts

in the tone arm T before the phonograph leaves the factory, the set screw may not be accessible to the purchaser, or some securing device other than a set screw may be employed. In such a phonograph the manufacturer so mounts the needle that the cg plane of the corundum point is approximately tangent to the edge of the turntable 23 when the point is aligned with the edge, and the c -axis $c-c$ is approximately parallel to the top of the turntable. Thus, proper positioning of the needle point when a record is placed on the turntable is assured.

We claim:

1. A phonograph needle comprising a shank having a set screw seat on a side adjacent the top thereof; and a unicyrstalline corundum point carried by said shank at the bottom thereof, said point being so positioned that the cg plane of said point approximately bisects said seat, and that the c -axis of said point and the longitudinal axis of the top portion of said shank form an angle of about 65° with one another on the side of said longitudinal axis remote from said seat.

2. A phonograph needle comprising a shank having a flat set screw seat on a side adjacent the top thereof; and a unicyrstalline corundum point carried by said shank at the bottom thereof, said point being so positioned that the cg plane of said point is approximately normal to said flat seat, and that the c -axis of said point and the longitudinal axis of the top portion of said shank form an angle of about 65° with one another on the side of said longitudinal axis remote from said flat seat.

3. A phonograph needle comprising a shank having a plane S-curve, and a unicyrstalline corundum point carried by said shank at the bottom thereof, said point being so positioned that the cg plane of said point parallels the plane of said S-curve, and that the c -axis of said point and the longitudinal axis of the top portion of said shank form an angle of about 65° with one another on the side of said longitudinal axis remote from said point.

4. A phonograph needle comprising a shank having a top for insertion in the tone arm of a phonograph and a unicyrstalline corundum point at the bottom of said shank, said needle having an index thereon so disposed with reference to the cg plane of said point and the c -axis position of said point that when said needle is positioned in a phonograph tone arm with said index in a position determined by a prearranged code, the cg plane of said point is approximately tangent to the sound track of a record to be played, and the c -axis of said point is approximately parallel to such record.

5. In a phonograph having a rotatable record table and a tone arm having a needle socket, a needle adapted to cooperate with a record on said table, said needle comprising a shank extending upwardly into said socket and a unicyrstalline corundum point at the bottom of said shank, said point being so positioned that the c -axis thereof is approximately parallel to said table and that the cg plane of said point is approximately tangent to the edge of said table, when said point is aligned with said edge.

6. In sound reproducing apparatus having a phonograph record provided with a sound track, a unicyrstalline corundum phonograph needle having a point riding in said sound track, the cg plane of said needle being approximately tangent to said sound track at the point of contact of said needle with said record, the c -axis of said

needle being approximately parallel to said record.

7. In sound reproducing apparatus having a rotatably mounted disc type phonograph record provided with a spiral sound track, a unicrystalline corundum phonograph needle having a point riding in said sound track, the *cg* plane of said needle being approximately tangent to said sound track at the point of contact of said needle with said record, the *c*-axis of said needle being approximately parallel to said record. 10

8. In a phonograph having a rotatable record table and a tone arm carrying a needle adapted to cooperate with a record on said table, said needle comprising a unicrystalline corundum point, the *cg* plane of said point being approximately tangent to the edge of said table when said point is aligned with said edge, and the *c*-axis of said point being approximately parallel to said record.
